UNITED STATES PATENT OFFICE.

DAVID S. HUSBAND, OF OAKVILLE, ONTARIO, CANADA.

WINDOW-VENTILATOR.

1,191,125.

Specification of Letters Patent. Patented July 11, 1916.

Application filed June 1, 1915. Serial No. 31,394.

To all whom it may concern:

Be it known that I, DAVID S. HUSBAND, a subject of the King of Great Britain, and resident of the village of Oakville, county 5 of Halton, Province of Ontario, in the Dominion of Canada, have invented certain new and useful Improvements in Window-Ventilators, described in the following specification and illustrated in the accompanying 10 drawings, that form part of the same.

The principal objects of the invention are, to provide a ventilator for windows which will effectually eliminate drafts and will insure the thorough ventilation of a room, and 15 to devise a construction wherein the inflow of air may be properly regulated.

The principal feature of the invention consists in the novel construction of a deflector member secured upon the inner side of 20 the window sash which deflector member is adapted to be adjusted to regulate the inflow of air and will at all times prevent a direct inflow to cause a draft, and whereby the opening in the sash communicating with the 25 deflector may be effectively closed.

In the drawings, Figure 1 is a perspective view showing the inner side of a window sash with my device attached thereto. Fig. 2 is an enlarged vertical cross sectional view 30 showing the device attached to a window sash.

Like numerals of reference indicate corresponding parts in each figure.

Referring to the drawings, 1 is the rail of 35 a window sash, here shown as representing the lower rail of the lower sash having an elongated orifice 2 extending horizontally therethrough.

3 is a member secured to the inner face 40 of the sash rail having the horizontally arranged plate portion 4 extending the full length of the orifice 2 and the upwardly turned ends 5. The ends 5 are formed with laterally extending lugs 6 which are secured 45 to the sash by suitable screws and the upper ends of the end portions 5 are turned laterally thus forming finger grips or pulls for lifting the sash.

7 are grooves formed in the upper surface 50 of the plate member 4 extending longitudinally thereof from end to end, the inner groove being immediately adjacent to the inner face of the sash.

8 are notches formed in the upper edge of 55 the end members 5 corresponding in number to the grooves 7 but spaced farther apart

than said grooves, the inner notch adjacent to the sash having a beveled edge 9.

10 is a plate loosely supported in the member 3 formed with a beveled bottom edge 60 adapted to fit snugly into the grooves 7. This plate extends the length of the member 3 fitting loosely between the end plates 5 and having end lugs 11 adapted to rest in and engage the notches 8. This plate is provided with a suitable handle 12 for use in lifting and adjusting the same and when the device is used upon an upper sash for allowing the egress of vitiated air from a room, the said plate may be formed with suitable 65 handle arrangements to allow of its being readily handled by means of a rod.

It will be readily seen that the plate 10 may be adjusted to any of the various positions with the lugs 11 resting in the notches 75 8 and the bottom edges of the plate resting in either of the grooves 7 and that when the said plate is placed in its innermost position it will effectively close the opening against the ingress of air. When the plate is moved 80 to its outermost position the area of the space inclosed between the said plates and the ends and the inner face of the sash is greater than the area of the orifice 2 in the sash 1 but it will be noted that at all times 85 any air entering through the opening in the sash rail will be deflected upwardly.

13 is a shield member arranged upon the outer side of the sash rail and here shown hinged at the top and provided with sector-shaped end pieces 14 extending into the orifice 2. This shield is adapted to prevent a current of air blowing with force directly through the orifice 2 and may be secured in a stationary position or may be adjusted in- 90 wardly or outwardly as desirable by any suitable means. I have shown herein a rod 15 slidably arranged in the sash and engaging an extending slotted lug 16 on said shield, said rod being hinged intermediate of its 100 length and having the inner end 17 provided with a knob 18 to form a handle which knob may be arranged to engage the ridges formed in the underside of the plate 4 to hold the shield in an outward position. When the 105 shield is drawn to the innermost position to close the orifice in the sash from the outer side the inner hinged end of the rod will swing downwardly to lock it close.

A window ventilator such as described is 110 very simple and cheap to construct and may be adjusted very quickly and allows of

thorough ventilation of a room without the detrimental effect of a straight passage or opening.

The member 3 is herein shown as having the plate portion 4 arranged in a horizontal position but it must be understood that this plate or bottom portion may be arranged at an incline from the surface of the sash if so desired.

10 What I claim as my invention is:—

1. In a window ventilator, the combination with the sash having an orifice therethrough, of a sheet metal member secured to the inner side of the sash having a horizontal plate projecting inwardly and extending the full length of the orifice, said member having rigid end walls, and a movable plate adapted to rest upon the inwardly extending plate member and to rise upwardly therefrom between the ends and adapted to be held in adjusted positions.

2. In a window ventilator, the combination with the sash rail having an orifice therethrough, of a sheet metal member secured to the inner face of said sash and having a plate portion extending longitudinally of the orifice and projecting inwardly from the sash and provided with longitudinal

grooves in its upper face and having end walls rising therefrom, said end walls having notched recesses, an adjustable plate member adapted to rest in the grooves in the longitudinal horizontal plate and adapted to engage the notches in said end plates and forming a baffle.

3. In a window ventilator, the combination with the sash rail having an orifice therethrough, of a member secured to the sash and extending longitudinally of the orifice and having upturned ends, said member having a longitudinal beveled surface adjacent to the face of the sash and grooves extending longitudinally parallel with said sash, the end portions of said member each having a notch adjacent to the sash formed with an inwardly beveled edge and notches in the upwardly extending portions, and an adjustable plate member adapted to extend between said end portions and having a beveled lower edge adapted to engage the longitudinal grooves in the aforesaid member, and projecting end portions adapted to engage the notches in said end plates.

Signed at the city of Toronto, Canada, this 18th day of May 1915.

DAVID S. HUSBAND.
